UNITED STATES PATENT OFFICE.

CHARLES E. ANDERSON AND CHARLES C. MCKILLIPS, OF LAKE ANDES, SOUTH DAKOTA.

GATE-OPERATOR.

1,066,692.

Specification of Letters Patent.

Patented July 8, 1913.

Application filed November 9, 1912. Serial No. 730,372.

To all whom it may concern:

Be it known that we, CHARLES E. ANDERSON and CHARLES C. MCKILLIPS, citizens of the United States, residing at Lake 5 Andes, in the county of Charles Mix and State of South Dakota, have invented certain new and useful Improvements in Gate-Operators; and we do declare the following to be a full, clear, and exact description of 10 the invention, such as will enable others skilled in the art to which it appertains to make and use the same.

This invention is a gate operator by means of which a gate of the lazy-tong type 15 may be opened from horseback or while the operator is seated in a wagon or on foot at either side of the gate, by drawing down on a handle connected with a lever so as to tilt the latter, and then may be closed by 20 the same operator after he has passed through the gate by drawing down on a handle connected with the other end of the lever; and the object of the same is to improve the construction of gate operators of 25 this character whereby the gate may be closed and then opened again from either side, whereby but a single post is required to support the gate and yet the same when closed may rest on a support in the fence 30 post on the opposite side of the roadway so that the weight of the gate is taken off this post to an extent, and whereby only a single element is attached to and hangs from the operating lever and its movement 35 up or down actuates the opening and closing mechanism. These objects are carried out by constructing the gate and the opening and closing mechanism in the manner hereinafter more fully described and 40 claimed, and as shown in the drawings wherein—

Figure 1 is a side elevation of this device attached to a gate which is closed. Fig. 2 is an elevation taken from the rear of the 45 post. Fig. 3 is an enlarged elevation of the inner end of the gate of Fig. 1, with the housing therein removed so that the actuating mechanism is better seen; and Fig. 4 is a vertical section on the line 4—4 of Fig. 50 3. Fig. 5 is a detail of the lower end of the connector, giving a side elevation of the actuating arms and the links with the outer ends of the latter depressed, and Fig. 6 is a similar view with the outer ends of the 55 links raised. These views show the position

of parts when the gate is open, whereas Fig. 3 shows the position of parts when the gate is closed. Fig. 7 is a horizontal section on the line 7—7 of Fig. 3. Fig. 8 is a perspective detail of the lip at the lower end of 60 the connector, and Fig. 9 is a perspective detail of the grooved plate with which said lip engages.

The gate G in the present case is of the lazy-tong type well known in this art, and 65 comprises crossed bars pivoted to each other where they cross as usual, and this gate stands between the fence F at one side of the roadway and a single post P at the other. To the upper end of the post is piv- 70 otted a lever L from each end of which hangs a rope R carrying a handle H, and said handles stand alongside the roadway at points sufficiently remote from the post to permit an operator approaching in a team 75 to reach out and draw downward on the handle to open the gate. The actuating mechanism for the latter is located at the base of the post P and preferably inclosed by a suitable casing C which may be of 80 sheet metal or otherwise. The free end of the gate is provided with a notch N which, when said gate is closed as seen in Fig. 1, rests on a support S such as a pin or nail in the side of the fence post F, whereby the 85 weight of this end of the gate is taken off of the single gate-post P.

No novelty is claimed for the parts thus far described and designated in the drawings by reference letters, the invention lying 90 in the peculiar form of the actuating mechanism as set forth below.

The inner end of the gate is supported on a main pivot 1 which is a screw or bolt set in the post P, and by preference this pivot 95 passes through what I will call hub plates 2 and 3 which are pivotally attached to the links of the lazy-tong gate as best seen in Fig. 3. At any rate, the pivot should pivotally connect with the gate at a point mid- 100 way between its top and bottom, and preferably one pair of links extends to the rear of the pivot and is concealed within the housing or casing C.

The numerals 4 and 5 designate arms, 105 each of which is by preference made double as seen in Fig. 4, and the upper ends of these arms are mounted on a common pivot 6 in the side of the post P directly above the main pivot, while their lower ends di- 110

verge and are pivotally connected as at 7 and 8 to two of the lazy-tong pivots at respectively opposite sides of the point 1 where the inner end of the gate is supported 5 by the post. It follows that when these arms are spread apart at their lower ends the lazy-tong structure is distended and the gate shot across the roadway, and when these arms are contracted at their lower ends the 10 lazy-tong structure is collapsed and the gate is retracted and therefore opened. The actuating mechanism preferably employed connects that arm of the lever L which stands over the gate and which moves vertically as the lever is turned on its pivot, with 15 said arms in such manner that they are swung to and fro around their common pivot 6; and said actuating mechanism must therefore be of such type that it will convert the 20 vertical movement of the lever into a horizontal movement of said arms in directions opposite to each other.

Pivots 15 and 16 for the actuating mechanism are provided at the extremities of said cross bar 14, and consist of rivets or bolts extending through it as seen in Fig. 4, their rear ends carrying the lip 17 best seen in Fig. 8, which, in the vertical movement of 30 said connector, travels up and down across the face of a plate 18 best seen in Fig. 9 and which is provided with a groove 19 into which said lip falls at a time when the lever L stands horizontal. The purpose of this 40 detail will be described below.

The actuating mechanism of itself comprises two links, or two separate links, which connect the lower end of the connector 11 with said pivoted arms 4 and 5, and it will 50 be obvious that when the connector is raised and lowered by the lever L the actuating mechanism must swing said arms apart and draw them toward each other again in order to expand and contract the gate as 55 above described. In the construction shown, the single link 20 is pivoted at its outer end on the bolt or rivet 15 between the cross bar 14 of the connector and the lip 17, and extends thence inward between the two arms 60 4, 4, and is pivoted at 21 between the other two arms 5, 5; and the pair of links 22, 22 are pivoted at their outer ends on the pivot 16 between the cross bar 14 and the lip 17, and extend thence inward astride the other 65 two arms 5, 5, past the pivot 21, and are

pivoted at 23 to the two arms 4, 4. The pivotal connecting point between the inner ends of all links and the arms stands in a line midway between the highest and the lowest positions of said cross bar 14 when the connector is raised and lowered, as shown in Figs. 5 and 6; and it follows that when the connector is depressed as by drawing down on one end of the lever L the links assume the position shown in Fig. 5, but when the connector is raised as by drawing down on the other lever L the links assume the position shown in Fig. 6. In either extreme position the arms are forced toward each other so that the lazy-tong gate 70 is collapsed, but when the links stand in a position intermediate between these two extremes, or in a horizontal line with each other as shown in Figs. 3 and 7, the arms 75 4 and 5 are spread apart from each other and the lazy-tong gate is distended. At 80 this time the lip 17 drops into the groove 19 of the plate 18 where it rests with some friction as seen in Fig. 4 and the gate will therefore remain held closed to the degree of this 85 friction as against the possible tendency of that end of the lever L carrying the connector 11 to descend by reason of its slightly greater weight. When the lever is tilted to move the links to either extreme position, 90 said lip moves out of the groove in the plate 18 and rises or falls as the case may be. We might say that this device constitutes a friction latch for holding the gate closed. For 95 holding it closed and yet without actually 100 latching or locking it, the notch N in its outer end will be caused to rest upon the support S in the fence post F in a manner well shown in Fig. 1.

With this construction of parts, an operator approaching from either side of the gate will find the lever L standing horizontal when the gate is closed. If he draw down on the nearest handle H he will tilt the lever, and this action moves the connector either up or down. Such movement carries the links to an oblique position as seen in either Fig. 5 or 6, and either position will force the arms 4 and 5 toward each other and collapse the gate which therefore opens from across the roadway so that the operator may pass through. On the other side he grasps the other handle H and draws the lever downward to a horizontal position, when the connector moves the parts 110 to their relative positions as illustrated in Fig. 3, and the gate is projected across the roadway behind the operator. If now it should so happen that he changes his mind and wants to pass again quickly through 115 the gate in the opposite direction, or possibly that he wants to open the gate for some one who is following him, he has but to pull down the same lever a little farther and the gate is again opened. Ordinarily, however, 120 125 130

he will leave the lever horizontal so that the lip rests within the groove as described above.

The proportions and materials of parts 5 are not essential to the successful operation of this invention, and in fact considerable change in details may be made without departing from its principle.

What is claimed as new is:

- 10 1. The combination with a gate of the lazy-tong type; of a main pivot supporting its inner end, a post in which the pivot is seated, a pair of arms connected at their lower ends with pivots in the gate structure 15 on opposite sides of its main pivot, a common pivot in the post on which the upper ends of said arms are supported, and means for swinging said arms apart or drawing them toward each other.
- 20 2. The combination with a gate of the lazy-tong type; of a main pivot supporting its inner end, a post in which the pivot is seated, a pair of arms connected at their lower ends with pivots in the gate structure 25 on opposite sides of its main pivot, a common pivot in the post on which the upper ends of said arms are supported, a lever pivotally mounted in the post alongside the roadway, actuating mechanism for drawing 30 said arms toward each other or spreading them apart, and connecting mechanism between the lever and actuating mechanism.
- 35 3. The combination with a gate of the lazy-tong type; of a main pivot supporting its inner end, a post in which the pivot is seated, a pair of arms connected at their lower ends with pivots in the gate structure 40 on opposite sides of its main pivot, a common pivot in the post on which the upper ends of said arms are supported, a lever pivotally mounted in the post alongside the roadway, actuating mechanism for drawing 45 said arms toward each other or spreading them apart, and a connector having a yoke at its upper end pivoted to said lever adjacent the post and side arms diverging

downward from said yoke and connected by a cross bar at their lower ends, and pivots between said cross bar and the actuating mechanism, for the purpose set forth. 50

4. The combination with a gate of the lazy-tong type; of a main pivot supporting its inner end, a post in which the pivot is seated, a pair of arms connected at their lower ends with pivots in the gate structure 55 on opposite sides of its main pivot, a common pivot in the post on which the upper ends of said arms are supported, a lever pivotally mounted in the post alongside the roadway, a connector depending therefrom 60 and having a wide lower end, a link pivotally connecting one extremity of said lower end with the opposite arm, and a second link connecting the other extremity thereof with the other arm. 65

5. The combination with a gate of the lazy-tong type; of a main pivot supporting its inner end, a post in which the pivot is seated, a pair of arms connected at their lower ends with pivots in the gate structure 70 on opposite sides of its main pivot, a common pivot in the post on which the upper ends of said arms are supported, a lever pivotally mounted in the post alongside the roadway, a connector depending therefrom 75 and having a wide lower end, link mechanism connecting one extremity of said lower end with the opposite arm and the other extremity with the other arm, a lip carried by said lower end, and a plate mounted on 80 the post and having a groove with which said lip engages when said links stand horizontal and said arms are spread apart.

In testimony whereof we have hereunto set our hands in presence of two subscribing witnesses. 85
